CHILD'S BED

Colleen Roberson Scoggins, Ranger, Tex.

Application August 31, 1955, Serial No. 37,729

Term of patent 7 years

(Cl. D5—4)

The single figure is a front perspective view of a child's bed, showing my new design.

The dotted lines showing the bed and cover outline are for illustrative purposes only.

I claim:

The ornamental design for a child's bed, as shown and described.
